UNITED STATES PATENT OFFICE.

WILLIAM H. FOX, OF MINNEAPOLIS, MINNESOTA.

PLAYGROUND BALL AND PROCESS OF PRODUCING THE SAME.

Application filed November 23, 1923. Serial No. 676,562.

To all whom it may concern:

Be it known that I, WILLIAM H. Fox, a citizen of the United States, residing at Minneapolis, in the county of Hennepin and 5 State of Minnesota, have invented certain new and useful Improvements in Playground Balls and Processes of Producing the Same; and I do hereby declare the following to be a full, clear, and exact description of the invention, such as will enable others skilled in the art to which it appertains to make and use the same.

My present invention provides an improved process of making play-ground balls 10 of the baseball type.

In the accompanying drawings, which illustrate the invention, like characters indicate like parts throughout the several views.

Referring to the drawings:

20 Fig. 1 is an elevation of the improved playground ball;

Fig. 2 is a transverse section taken centrally through said ball;

25 Fig. 3 is a view in diagram showing, by means of full lines, the two cover sections in their relative arrangement in which they will be wrapped around a body, and by means of dotted lines, the upper cover section is shown in position on the lower cover 30 section to receive the first stitches in connecting said sections; and

Fig. 4 is a detail view in section taken transversely through one of the seams between the cover sections on an enlarged 35 scale.

It is thought that the description of the improved playground ball will be best understood by giving the progressive steps in the process of producing the same, and 40 the first step is to cut, preferably by dies, two duplicate 8-shaped cover sections 5 and 6 of leather or other suitable material, and each of said sections has a circular end portion and concave intermediate edge portions. 45 These two cover sections 5 and 6, when their outer edge portions are connected by stitches, form a sphere for receiving a body member, as will hereinafter appear.

At the time the cover section 5 is formed 50 there is also formed thereon a central longitudinal slot 7 of such length as to extend substantially throughout one-half of the circumference of the sphere formed by the cover sections 5 and 6. At this same time, 55 needle holes 8 are punched in the longitudinal edge portions of the cover section

5 at the slot 7. Preferably, as shown, the slot 7 is located with its ends equidistant from the ends of the cover section 5 but it is, of course, understood that said slot may be formed by slitting said cover section through one end thereof and extending said slit a distance sufficient to form the slot 7. 60

The next step is in skiving the marginal edge portions of the cover sections 5 and 6 65 to relatively thin edges 9.

The next step is in placing the cover section 5 over one of the rounded ends of the cover section 6, as indicated by broken lines in Fig. 3, and with the finished or 70 outer faces of the cover sections turned toward each other.

The next step is in connecting the overlapped edge portions of the cover sections 5 and 6, preferably by sewing the same on a power machine, to produce stitches 10. 75 This sewing is preferably started at 11, and to bring the marginal edge portions of the cover sections 5 and 6 into overlapping arrangement to receive the stitches 9, one of said cover sections is turned or rotated in respect to the other and in a plane parallel thereto. At the completion of the sewing of the cover sections 5 and 6 together, the cover is wrong side out and the stitches 10 and free edge portions of the cover sections at the 8-shaped seam 12 are on the outside 80 of the said cover. To turn the cover right side out, the same is inserted through the slot 7 to bring the skived edges 9 and 85 stitches 10 on the inside of the cover so that the seam 12 on the outside of the cover is smooth.

The next step is in providing a relatively solid preformed body 13 of any suitable construction and inserting the same through the slot 7 and into the cover. The size of this body 13 is such that the cover will be tightly drawn thereover. 90

The next step is in closing the slot 7 by 100 drawing the respective edge portions of the cover section 5 together by means of double stitches produced by inserting suitable thread 14 through the needle holes 8. At the completion of the closing of the slot 7, the ends of the thread are tied in a knot 15, and said knot inserted through the slot 7 between the cover and body 13. 105

The purpose of skiving the edges 9 is to 110 reduce the stock and make the edges relatively pliable so that they will be folded or turned and thereby more easily embedded.

in the body 13. If necessary, the cover may be slightly pounded along the 8-shaped seam 12 to cause the edges 9 and stitches 10 to completely embed themselves in the body 13 so as to leave the exterior of the ball perfectly smooth without any ridges or uneven spots.

The above described process of forming the cover for a playground ball makes it possible to do all of the sewing, in connecting the 8-shaped sections thereof, on a power machine which materially reduces the cost of manufacture. This process also brings the stitches 10 on the inside of the cover so that they are invisible and immune from wear.

In some instances it may be desirable to dispense with the slot 7, and leave an opening in the seam 12 through which the cover can be inserted to turn the same inside out and through which the body 13 may be inserted within the cover. This opening could thereafter be closed by stitches to produce an inseam.

25. What I claim is:

1. The process of forming a cover for a playground ball which consists in providing sections which, when connected, form a sphere, forming a slot in one of said sections, overlapping the edge portions of said sections and connecting the same with stitches, and inserting said cover through the slot to turn the same inside out and bring said stitches and the free edge portions of said sections on the inside of the cover.

2. The process of forming a playground ball which consists in providing cover sections which when connected form a sphere, forming a slot in one of said sections, overlapping the edge portions of said sections, connecting the same with stitches, inserting said cover through the slot to turn the same inside out and bring said stitches and the free edge portions of said sections on the inside of the cover, inserting a pre-formed relatively solid body through said slot and into the cover, and drawing the edges of the cover together at the slot to close the same.

3. The process of forming a cover for a playground ball which consists in providing two 8-shaped sections which when connected form a sphere, forming a slot in one of said sections, laying one end of one of said sections transversely across the intermediate portion of the other of said sections, stitching the edge portions of the sections together, during the turning of one of said sections in respect to the other to bring the edge portions of said sections into overlapping relation, and inserting the cover through said slot to turn the cover inside out and bring said stitches and the free edge portions of said sections on the inside of the cover.

4. The process defined in claim 2 includ-

ing a further step in skiving the free edge portions of said sections to relatively thin edges.

5. The process of forming a playground ball which consists in providing two 8-shaped cover sections which when connected form a sphere, forming a slot in one of said sections, overlapping the edge portions of said sections and connecting the same with stitches, inserting said cover through the slot to turn the same inside out and bring said stitches and the free edge portions of said sections on the inside of the cover, inserting a pre-formed relatively solid body through said slot and into the cover, drawing the edges of said cover together at the slot with double stitches to close the same, tying the ends of said stitches, and inserting the same through the slot and within the cover.

6. The process of forming a playground ball which consists in cutting two 8-shaped sections which when connected form a sphere, cutting a slot in one of said sections and forming needle holes in the marginal edge portions of said section at said slot, overlapping the edge portions of said sections, connecting the same with stitches, inserting said cover through the slot to turn the same inside out and bring said stitches and the free edge portions of said cover sections on the inside of the cover, inserting a pre-formed relatively solid body through said slot and into the cover, and running a thread through said needle holes to draw the edges of the cover together at the slot to close the same.

7. The process of forming a cover for a playground ball which consists in providing sections which when connected form a sphere, overlapping the edge portions of said sections, connecting the same with stitches, inserting said cover through an opening in the cover to turn the same inside out and bring said stitches and the free edge portions of said sections on the inside of the cover, inserting a pre-formed relatively solid body through said opening, and drawing the edges of the cover together at the opening to close the same.

8. The process of forming a cover for a playground ball which consists in providing sections which when connected form a sphere, leaving an opening in the cover, overlapping the edge portions of said sections and connecting the same with stitches, inserting said cover through said opening to turn the same inside out and bring the stitches and the free edge portions of said sections on the inside of the cover, inserting a pre-formed relatively solid body through said opening, and closing said opening.

In testimony whereof I affix my signature.
